ABSTRACT OF THE DISCLOSURE

Water-insoluble thiazolyl-azo-aniline compounds in which the nitrogen atom of the aniline coupling component is substituted by a dicarboximidoethyl-sulfonyethyl group are useful as dyes for hydrophobic textile materials.

This invention relates to novel water-insoluble azo compounds and, particularly, to thiazolylazo dyes for hydrophobic textile fibers, yarns and fabrics.

The novel azo compounds of the invention are characterized by the general formula

wherein

R represents a thiazolyl radical, e.g. a radical having the structure:

wherein X represents the various substituents that can be present on the thiazolyl ring, representative examples of which are hydrogen; alkyl, e.g. methyl, ethyl; substituted alkyl such as halogenoalkyl, e.g. chloromethyl, trifluoromethyl, cyanoalkyl, e.g. cyanoethyl, nitroalkyl, e.g. nitroethyl, hydroxyalkyl, e.g. hydroxyethyl; alkoxy, e.g. methoxy; acylamido, e.g. acetamido; nitro; halogeno, e.g. chloro, bromo; cyano; alkylsulfonyl, e.g. methylsulfonyl, substituted alkoxy, e.g. halogenoalkoxy; substituted alkylsulfonyl, e.g. cyanoethylsulfonyl; carbamoyl; N-alkylcarbamoyl, e.g. N,N-dimethylcarbamoyl; phenyl; benzyl; benzoyl; benzamido; benzylamino; N-alkylbenzylamino; N-alkylarylamino, e.g. N-methylphenylamino; alkoxy carbonyl, e.g. ethoxycarbonyl; hydroxyl; acyl, e.g. acetyl; formyl; sulfamoyl; N-alkylsulfamoyl, e.g. N-ethylsulfamoyl; alkylsulfonamido, e.g. methylsulfonamido, ethylsulfonamido; substituted alkylsulfonamido, e.g. cyanoethylsulfonamido, dicarboxylic acid imido, e.g. succinimido; thiocyanato; alkylthio, e.g. methylthio; benzoyl; combinations thereof; and m represents 1 or 2.

R¹ represents a monocyclic carbocyclic aromatic group of the benzene series having the structure

wherein Y represents the substituents present on the phenylene ring, illustrative examples of which are hydrogen, alkyl, e.g. methyl, ethyl; substituted alkyl such as halogenoalkyl, e.g. chloromethyl, cyanoalkyl, e.g. cyanoethyl, nitroalkyl, e.g. nitroethyl, hydroxyalkyl, e.g. hydroxyethyl; alkoxy, e.g. methoxy; substituted alkoxy, e.g. cyanoethoxy; acylamido, e.g. acetamido; halogeno, e.g. chloro, bromo; phenyl; phenylalkyl, e.g. benzyl; benzamido; benzylamino; N-alkylarylamino, e.g. N-methylphenylamino, hydroxyl, alkylsulfonamido, e.g. methylsulfonamido, ethylsulfonamido; substituted alkylsulfon-

amido, e.g. chloroethylsulfonamido; dicarboxylic acid imido, e.g. succinimido; thiocyanato; alkylthio, e.g. methylthio; benzoyl; combinations thereof; and n represents 1, 2 or 3;

R² represents hydrogen or an alkyl radical, preferably lower alkyl, i.e. from 1 to 4 carbon atoms, being non-substituted or substituted such as hydroxyalkyl, e.g. hydroxyethyl, polyhydroxyalkyl, e.g. 2,3-dihydroxypropyl, alkoxyalkyl, e.g. methoxyethyl, cyanoalkyl, e.g. cyanoethyl, cyanoalkoxyalkyl, e.g. β-cyanoethoxyethyl, acyloxyalkyl, e.g. acetoxyethyl, alkoxy carbonylalkyl, e.g. ethoxycarbonylalkyl, halogenalkyl, e.g. chloroethyl, α-chloropropyl, bromoethyl, hydroxyhalogenoalkyl, e.g. 3-chloro-2-hydroxypropyl, alkylsulfonylalkyl, e.g. methylsulfonylalkyl, alkyl-OOCOCH₂CH₂—, e.g.

e.g. carbamoylalkyl, e.g. carbamoylethyl, dicarboxylic acid imidoalkyl, e.g. succinimidoethyl, phthalimidoethyl; benzyl; phenoxyalkyl, e.g. β-phenoxyethyl; alkylsulfonylalkyl, e.g. methylsulfonylalkyl; N-alkylcarbamoylalkyl, e.g. N-ethylcarbamoylalkyl; dicarboxamidoalkyl, e.g. β-dicarboximidoethyl; e.g. carbamatoalkyl, e.g. carbamatoethyl; and the like; or R₂ represents a monocyclic carbocyclic aromatic radical of the benzene series, e.g. nonsubstituted phenyl and substituted phenyl such as represented by the monovalent analog of R₁ above, e.g. alkylphenyl, alkoxyphenyl, nitrophenyl, alkylsulfonylphenyl, etc. A preferred group represented by R₂ includes hydrogen, alkyl, alkoxyalkyl, phenoxyalkyl, acyloxyalkyl, haloalkyl, hydroxyalkyl, ethoxycarbonylalkyl, carbamoylalkyl, alkylsulfonylalkyl or cyanoalkyl, the alkyl groups of which are lower alkyl;

R₃ represents a dicarboximido group, i.e. a dicarboxylic acid imido group having the structure:

wherein Z represents a hydrocarbon radical or group of carbon atoms necessary to complete a ring, preferably a ring containing 4 or 5 carbon atoms in addition to the imido nitrogen atom, i.e. the hydrocarbon residue of the dicarboxylic acid anhydride from which the radical is derived. The divalent hydrocarbon group can be a straight or branched chain, saturated or unsaturated divalent aliphatic group such as alkylene, e.g. ethylene, pentamethylene, isopropylene, isobutylene; alkenylene, e.g. vinylene (—CH=CH—), which can be substituted with various groups such as those present on the alkyl groups represented by R₂ above, for example, halo, e.g. chloro, bromo, hydroxy, nitro, cyano, acyloxy, e.g. acetoxy, etc. The divalent hydrocarbon group represented by Z can also be a divalent carbocyclic group such as the mono- and bi-cyclic aromatic groups and the mono- and bi-cyclic non-aromatic groups, examples of which are o-phenylene, 1,8-naphthylene, 2-cyclohexylene, bicyclo[2.2.1]-5-heptenylene, etc. Like the aliphatic hydrocarbon groups, the divalent carbocyclic groups can be substituted with many groups such as, for example, those represented by X in relation to the definition of R above. The more preferred groups represented by Z are an alkylene group of 2 to about 4 carbon atoms and a phenylene group.

Upon reading the following examples further describing and illustrating the invention, it will be apparent that numerous variations in the substituents represented by X and Y and those on the groups represented by R² and R³ can be made without materially affecting the dye affinity of the compounds of the invention. As can be seen from the examples given below, the substituents attached to the groups represented by R, R¹, R² and R³ serve primarily

3

as auxochrome groups to control the color of the azo compound and, thus, are not critical. The alkyl groups represented by X, Y and R² can consist of many carbon atoms in a straight or branched chain, e.g. dodecyl, 3-ethylhexyl. However, for reasons of economy and availability, the preferred alkyl groups are lower alkyl, i.e. up to about four carbon atoms. For similar reasons, the alkyl moiety of the various substituents that can be present on the groups represented by R, R¹, R² and R³ are preferably carbon chains of up to about four carbon atoms. As used herein, the term acyl refers to the residue of a carboxylic acid having the formula ACO wherein A is an aliphatic or carbocyclic group.

The novel azo dyes of the invention, characterized by Formula I above, are prepared by coupling a conventional diazonium salt of an aminothiazole compound having the structure:

with a coupling component having the structure:

Thus, the schematic reaction is illustrated as follows:

The coupling components represented by structure (III), above, are prepared by the reaction of an alkyl- or an aryl-dicarboxylic acid imide with a vinylsulfonylethylaniline derivative, the reaction being schematically illustrated as follows:

The preparation of the coupling components and the dyes produced therefrom will be more fully illustrated by the following examples.

PREPARATION OF THE COUPLERS

N-2-(2-succinimidoethylsulfonyl)ethyl-N-ethyl-m-toluidine

One ml. of 40% aqueous Triton B is added to a stirred slurry of 4.45 g. succinimide, 0.5 g. hydroquinone and 25 ml. dioxane. A solution of 12.65 g. N- β -vinylsulfonyl-ethyl-N-ethyl-m-toluidine (prepared by the reaction of N-ethyl-m-toluidine and divinylsulfone in the presence of acetic acid and a hydrocarbon solvent) in 15 ml. dioxane is added dropwise during 15 minutes. The reaction mixture is stirred and heated at reflux for 2½ hrs., then drowned in water. The solid coupler which forms is crystallized from ethanol. It has the structure:

4

N-2-(2-succinimidoethylsulfonyl)ethyl-N-ethylaniline

In accordance with the above procedure, succinimide is reacted with N- β -vinylsulfonylethyl-N-ethylaniline to obtain the coupler having the structure:

N-2-(2-phthalimidoethylsulfonyl)ethyl-N-ethyl-m-toluidine

In accordance with the above procedure, phthalimide is reacted with N- β -vinylsulfonylethyl-N-ethyl-m-toluidine to obtain the coupler having the structure:

N-ethyl-N-2-(2-phthalimidoethylsulfonyl)ethyl-m-chloroaniline

In accordance with the above procedure, phthalimide is reacted with N- β -vinylsulfonylethyl-N-ethyl-m-chloroaniline to obtain the coupler having the structure:

Preparation of the dyes

EXAMPLE 1

An amount of 2.90 g. of 2-amino-5-nitrothiazole is dissolved at room temperature in 25 ml. of water and 13.5 ml. conc. H₂SO₄. This solution was cooled to -10° C. and 1.54 g. NaNO₂ in 10 ml. H₂SO₄ was added below 0° C. The solution is stirred 10 min. and added to a solution of 8.00 g. of N-2-(2-phthalimidoethylsulfonyl)ethyl-N-ethyl-m-toluidine in 100 ml. 1:5 acid (1 part propionic acid:5 parts acetic acid) at 5° C. After 30 min. the reaction mixture is drowned in water and the precipitated dye filtered, washed with water and air dried. The product dyes polyester fibers blue-violet shades of excellent sublimation fastness. The dye has the structure:

EXAMPLE 2

Nitrosyl sulfonic acid is prepared by dissolving 1.62 g. NaNO₂ in 12 ml. conc. H₂SO₄ below 80° C. The solution is cooled to 15° and 25 ml. 1:5 acid is added below 20° C. After further cooling to -2°, 5.60 g. 2-amino-5-bromothiazole hydrobromide is added below 3° C. followed by 25 ml. 1:5 acid below 5° C. After stirring for ½ hr. at -5° to +5° C. the solution is added to 6.84 g. of N-2-(2-succinimidoethylsulfonyl)ethyl-N-ethyl-m-toluidine in 50 ml. 1:5 acid. Solid ammonium acetate is added until a brown color on Congo Red paper is obtained and after 1½ hr. the reaction mixture is drowned in water. The precipitated dye is filtered, washed with water and air dried. It dyes polyester fibers and cellulose acetate red-violet shades and displays excellent sub-

5

limation fastness on polyester fibers. The dye has the following structure:

EXAMPLE 3

A diazonium solution is prepared from 2.90 g. of 2-amino-5-nitrothiazole as in Example 1. The solution is added to 6.84 g. of N-2-(2-succinimidomethylsulfonyl)ethyl-N-ethyl-m-toluidine in 50 ml. 1:5 acid. The dye is worked up as in Example 1. It gives blue-violet shades on polyesters and cellulose acetate of good light fastness and excellent sublimation fastness on polyesters. It has the structure:

EXAMPLE 4

A diazonium solution is prepared from 2.90 g. of 2-amino-5-nitrothiazole as in Example 1. This solution is added to 6.56 g. of N-2-(2-succinimidomethylsulfonyl)ethyl aniline in 50 ml. 1:5 acid. The dye is worked up as in the Example 1. It gives violet shades on polyesters and cellulose acetate. The dyeings have excellent sublimation fastness on polyesters and good light fastness on both fibers.

It has the structure:

EXAMPLE 5

A diazonium solution is prepared as in Example 1 from 2.90 g. of 2-amino-5-nitrothiazole. This solution is added to 8.40 g. of N-ethyl-N-2-(2-phthalimidomethylsulfonyl)ethyl-m-chloroaniline in 50 ml. 1:5 acid. The dye is worked up as in Example 1. It dyes polyester and cellulose acetate fibers a violet shade having good light fastness and good sublimation fastness on polyesters. It has the structure:

The thiazolylazo compounds set forth in the following table are prepared according to the procedure described in the above Examples. The appropriate aminothiazole compounds of Formula II are diazotized and coupled with the coupler compounds of Formula III to yield the compounds of Formula I. The color of the compounds refers to dyeings on polyester fibers.

TABLE

Example	X	R ¹	R ²	Z	Color

20	4-CO ₂ C ₂ H ₅	o-Chlorophenylene	H		Red.
21	4-NHCOCH ₃	m-Chlorophenylene	-C ₂ H ₅		Red.
22	None	2-OCH ₃ -5-NHCOCH ₃ phenylene	-C ₂ H ₅	Same as above	Red-violet.
23	4-CH ₃ -5-COCH ₃	2-OCH ₃ -5-CH ₃ -phenylene	-C ₂ H ₅	do	Red.
24	5-CN	2,5-di-OCH ₃ -phenylene	-C ₂ H ₅	do	Red.
25	5-SCN	2-OCH ₃ -5-Cl phenylene	-C ₂ H ₅		Red.
26	5-SO ₂ CH ₃	do	-C ₂ H ₅	Same as above	Red.
27	4-phenyl	do	-C ₂ H ₅		Red.
28	4-CH ₃ -5-SCN	do	-C ₂ H ₅	Same as above	Red.
29	4-CH ₃ -5-NO ₂	do	-C ₂ H ₅	do	Violet.

The azo compounds of the invention can be used for dyeing textile materials, including protein and synthetic polymer fibers, yarns and fabrics, giving a variety of fast brilliant red to violet shades when applied thereto by conventional dye methods. The azo compounds have high affinity for cellulose ester, polyester, and nylon fibers. When the compounds are used for dyeing such hydrophobic materials, they should be free of water-solubilizing groups such as sulfo and carboxyl. In general, the dyes have excellent fastness, for example, to light, washing, gas (atmospheric fumes) and sublimation. The dyes are especially sublimation resistant on polyesters.

As described above, the present azo compounds have the characteristic structure of Formula I. This distinctive structure imparts unexpected properties to the compounds, including the above-described light fastness and sublimation resistance. Thus, we have found the compounds of the invention to possess excellent properties when used as dyes on hydrophobic textile materials, especially polyester, when tested by methods such as described in the A.A.T.C. Technical Manual, 1965 edition.

The compounds of the invention can be used for dyeing hydrophobic fibers such as linear polyester, cellulose ester, acrylic, polyamide, etc., fibers in the manner described in U.S. Pats. 2,880,050, 2,757,064, 2,782,187 and 2,043,827. The following example illustrates a method by which the azo compounds of the invention can be used to dye polyester textile materials.

0.1 g. of the dye is dissolved in the dye pot by warming in 5 cc. of ethylene glycol monomethyl ether. A 2% so-

dium-N-methyl-N-oleyl taurate and 0.5% sodium lignin sulfonate aqueous solution is added, with stirring, until a fine emulsion is obtained. Water is then slowly added to a total volume of 200 cc. Then, 3 cc. of Dacronyx (a chlorinated benzene emulsion) are added and 10 grams of a textile fabric made of Kodel polyester fibers are entered. The fabric is worked 10 minutes without heat and then for 10 minutes at 80° C. The dye bath is then brought to the boil and held at the boil for one hour. Following this, the fabric is rinsed in warm water, then scoured in aqueous 0.2% soap, 0.2% soda ash solution. After scouring, the fabric is rinsed with water and dried. Accordingly, since the compounds of the invention are water-insoluble, they can be applied from aqueous dispersions in the manner of the so-called "dispersed dye." However, coloration can also be effected, for example, by incorporating the compounds into the spinning dope and spinning the fiber as usual.

The compounds of the invention are not necessarily equivalents when used as dyes. The degree of dye affinity and fastness properties vary to some degree, for example, depending upon the material being dyed and the formula of the azo compound. Thus, for example, all the compounds will not have the same degree of dye affinity for the same material. For example, the substituents X, Y and R² serve primarily as auxochrome groups to control the color of the azo compound.

Polymeric linear polyester materials of the terephthalate type are illustrative of the linear aromatic polyester textile materials that can be dyed with the new azo compounds of

our invention. The terephthalate fibers sold under the trademarks "Kodel," "Dacron," and "Terylene," for example, are illustrative of the polyester textile materials that can be dyed. Kodel polyester fibers are more particularly described in U.S. Pat. 2,901,446. Dacron and Terylene polyester fibers are described, for example, in U.S. Pat. 2,465,319. The polymeric linear polyester materials disclosed in U.S. Pats. 2,945,010, 2,957,745 and 2,989,363 for example, can be dyed. The linear aromatic polyester materials specifically named have a melting point of at least 200° C.

Nylon, in fiber, yarn and fabric form, is representative of polyamides which can be dyed with the azo compounds.

We claim:

1. A water-insoluble compound having the formula

wherein

X is hydrogen, lower alkyl, lower alkoxy, acetyl, formyl, acetamido, nitro, chlorine, bromine, trifluoromethyl, cyano, lower alkylsulfonyl, carbamoyl, phenyl, benzyl, benzamido, lower alkoxy carbonyl, sulfamoyl, lower alkylsulfonamido, thiocyanato, lower alkylthio, or benzoyl;

m is 1 or 2;

Y is hydrogen, lower alkyl, lower alkoxy, chlorine, bromine, acetamido, lower alkylsulfonamido, or benzamido;

n is 1 or 2;

R² is hydrogen; lower alkyl; lower alkyl substituted with hydroxy, lower alkoxy, cyano, acetoxy, lower alkoxy carbonyl, chlorine, bromine, lower alkylsulfonyl, carbamoyl, lower alkyl carbamoyl, lower alkylsulfonamido, phenoxy, succinimido, or phthalimido; lower alkyl—OCOOCH₂CH₂—

benzyl; phenyl; or phenyl substituted with lower alkyl, lower alkoxy, chlorine, bromine, nitro, or lower alkylsulfonyl; and

Z is alkylene of 2 to 4 carbon atoms, hydroxyethylene, acetoxyethylene, chloroethylene, cyanoethylene, vinylene, o-phenylene, 1,8-naphthylene, 1,2-cyclohexylene, 50 1,2-cyclopentylene, or bicyclo [2.2.1]-5-heptenylene; and wherein

lower designates a carbon content of from 1 to 4 carbon atoms.

2. A compound defined in claim 1 wherein

X is nitro, chlorine, bromine, cyano, trifluoromethyl, lower alkylsulfonyl, or lower alkoxy carbonyl;

m is 1;

Y is hydrogen, lower alkyl, lower alkoxy, chlorine, bromine, or acetamido;

n is 1 or 2; and
R² is lower alkyl or lower alkyl substituted with lower alkoxy, phenoxy, acetoxy, chlorine, bromine, hydroxy, ethoxycarbonyl, carbamoyl, lower alkylsulfonyl, or cyano.

5 3. A compound as defined in claim 1 having the formula

15 4. A compound as defined in claim 1 having the formula

25 5. A compound as defined in claim 1 having the formula

6. A compound as defined in claim 1 having the formula

7. A compound as defined in claim 1 having the formula
